UNITED STATES PATENT OFFICE.

ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS.

WASHING MACHINE.

Original application filed January 18, 1922, Serial No. 530,012. Divided and this application filed April 4, 1925. Serial No. 20,629.

This invention has reference to washing machines and relates particularly to that type of machines intended for domestic use in the home.

5 The invention has for its principal object to improve the frame structure in which to mount the washing element and operating means therefor.

10 This application is a division of the application filed by me January 18, 1922, bearing Serial No. 530,012.

15 That the invention may be more fully understood reference is had to the accompanying drawings, forming a part of the description, illustrating a preferred embodiment of the invention, in which:—

Figure 1 is a side elevation of a washing machine frame embodying my invention;

20 Figure 2 is an end elevation of the frame looking in at the right hand side of Figure 1, and

25 Figure 3 is a vertical cross-section, as the same would appear, if taken on the line 3—3 Figure 1.

Like characters of reference denote corresponding parts throughout the figures.

The frame includes spaced end supports 1, 1, preferably made of angle iron and each bent into the form of an inverted U, but 30 with the upper arcuate end of each frame resembling more an inverted V, which not only makes a saving in material, but which also beautifies the design of the frame. To the lower end of each leg of the end supports is 35 secured a bracket 2 carrying a caster-wheel 3 to make the machine portable and for ease and convenience in moving the machine from place to place. The lower ends of the legs of each end support are connected and braced 40 by the angle-iron bars 4, and the corresponding legs of the opposite end supports are connected and braced by the angle iron bars 5. The sides of the machine are closed by the panels 6 and the ends are closed by the 45 panels 7. The side panels 6 cover the entire area of the end supports, see Figure 1, being bolted or otherwise secured to the supports 1, as at 8, except that the panels 6 on the side of the machine adjacent the operating means is preferably provided with a cut-out portion or opening 9 for easy access to the operating means, and said cut-out por-

tion or opening is preferably closed by the removable plate 10, see Figures 1 and 3 held in place by a suitable fastening 11, one member of which engages against a cross brace-bar 12 connecting the legs of the end support. A brace bar, such as 12, being provided for each end support, see Figure 3. The end panels, as shown in Figure 2, preferably do not extend to the top of the end supports 1, but rather stop approximately on a line with the top of the perpendicular leg portions of said supports at which point cross-brace bars 13 connect the opposite end supports said panels being bolted or otherwise secured to the end supports 1, as at 14. Included in the frame structure is a platform, comprising the cross-bar 15 and the bar 16 connecting said cross-bar 15 and one 60 of the brace-bars 4; also the motor rest 17 preferably resting on the bar 16 and one of the brace-bars 4. The cylinder of the washing machine is designated 20 and is supported by bearings 21 which latter are secured to the inner face of the V-shaped parts of the side panels 6, so that the V-shaped parts of the angle bars enclose and overhang the 65 bearings and protect the latter.

70 While I have shown and described the preferred form and manner of constructing the machine, it is obvious that various changes may be made without departing from the spirit and scope of the invention, and I, therefore, do not wish to be limited to 75 the precise details, except as stated in the appended claim.

What I claim is:—

80 A frame for washing machines, including spaced side members each composed of an integral angle bar bent to form similar spaced supporting legs connected by an inverted substantially V-shaped top part, side panels conformably fitted in the side members, end panels connected to the legs and 85 having their upper edges substantially aligned with the upper parts of the legs and cylinder bearings secured to the inner faces of the V-shaped parts of the side panels, the V-shaped parts of the angle bars enclosing and 90 overhanging said bearings.

95 In witness whereof, I have hereunto affixed my hand this 2nd day of April, 1925.

ALPHEUS W. ALTORFER.
